Patented Oct. 4, 1921.

Inventor
Joseph Amato
By his Attorney
Maxwell E. Sparrow

UNITED STATES PATENT OFFICE.

JOSEPPE AMATO, OF OSSINING, NEW YORK.

PEN OR PENCIL HOLDER.

1,392,388.

Specification of Letters Patent.

Patented Oct. 4, 1921.

Application filed April 13, 1921. Serial No. 461,130.

To all whom it may concern:

Be it known that I, JOSEPPE AMATO, a citizen of the United States, and resident of Ossining, in the county of Westchester 5 and State of New York, have invented certain new and useful Improvements in Pen or Pencil Holders, of which the following is a specification.

This invention relates to improvements in pen or pencil holders.

An object of this invention is to provide a simple, effective and efficient pen or pencil holder, which may be secured within the pocket of a garment or to a belt, said holder being adapted to not only hold the article but also to prevent same from being lost or stealthily removed.

Another object of this invention is to provide in such device a pair of clamping members co-acting in such manner as to firmly grip the article placed thereinbetween.

The above and further objects will more fully be understood from the following description together with the accompanying drawings, forming part of this specification and in which:

Figure 1 is a front view of this invention showing same in operation.

Fig. 2 is a side view of same.

Fig. 3 is an enlarged top view of same.

Fig. 4 is a vertical section through same (without the engaged article), taken on line 4-4 of Fig. 1.

Fig. 5 is an enlarged cross section through same (without the engaged article), taken on line 5-5 of Fig. 1.

In the drawings there is disclosed a holder made from any suitable material, preferably aluminum, or any other light weight metallic substance, engaging a fountain pen 10. This holder is provided with a base or plate member 11, slightly tapered and rounded at its bottom end 12.

The top end of base member 11 is provided with an extension which after being bent backward upon itself and riveted by means of rivets 13, forms a pair of ears 14 which provide pivot seats 15 and an upwardly projecting tongue 16 disposed intermediate ears 14.

Pivotedly secured in pivot seats 15 is a fabric clasp 17, said clasp being so disposed as to engage tongue 16 in such manner that the latter acting in spring fashion keeps the clasp in engaged position.

Secured to base 11 below ears 14 and at

right angles thereto, is an annular band or strap 18. Pivotedly secured to annular band 18 by means of pins 19, are the clamp members 20, the latter being adapted to be 60 swung outwardly, and laterally.

Clamping members 20 are provided at their upper ends 21 with off-set extensions which terminate in beads 22, so as to form a greater working distance through which 65 the clamps may be operated, while the portions below the pivoting points are bent inwardly.

The gripping portions of clamping members 20 comprise semi-cylindrical shaped 70 jaws 23, provided with teeth bent slightly inward, so as to bind or grip the article coming in contact therewith (in the drawings fountain pen 10). Within each jaw 23 there is secured a strip of frictional material 24, 75 the object of which is to assist jaws 23 in gripping the article.

The clamping members 20 are held in gripping or engaged position by means of a wire spring 25, so bent as to pass over an annular band 18 and engage the clamping members just above the jaws. The spring being so disposed always tends to bring the clamping members together.

Two straps 26 and 27 respectively, made 85 preferably of the same material as base 11 are provided. These straps are secured to base 11 at a right angle thereto, by having their ends pass through perforations formed in the latter, and then bent inwardly, as 90 clearly shown in Fig. 5.

Strap 26 encompasses clamping members 20, thereby preventing the latter from being spread too much apart when opened to permit fountain pen 10 being inserted in the 95 holder.

Straps 26 and 27 are adapted to receive fountain pen 10 and hold same against base 11.

The operation of this device is evident. 100 The jaws 23 of clamping members 20 are spread apart by pressing together and inwardly the upper ends 21. Fountain pen 10 or other suitable article is passed within annular band 18 and strap 27 and between 105 jaws 23, while the latter are kept spread apart, the band and strap holding the pen in vertical position.

The clamping members which are now released grip the pen, thereby preventing it 110 from being lost or stealthily withdrawn. To remove the pen, the clamping members

are spread apart in the manner stated above.

This device is adapted to be attached to the pocket of a garment or any other part 5 provided with an open end, such as a pair of trousers or a belt.

When it is desired to attach the device to a pocket, it is placed therewithin in such 10 manner that the back or base 10 rests against the side forming the open end of the pocket and the edge of the fabric is engaged by 15 clasp 17.

Having thus described my invention, I 15 reserve for myself the right to make alteration and amendments within the scope of 20 my idea.

What I claim is:

1. A pen or pencil holder comprising in 20 combination, a base provided with means for receiving an article, a pair of clamping members pivotedly disposed over said base, and a spring adapted to keep said clamping members in engaged position.

2. A pen or pencil holder comprising in 25 combination, a base, a clasp pivotedly secured to the back of said base, a pair of clamping members pivotedly disposed over said base, a spring adapted to keep said clamping members in engaged position, and 30 means for receiving a pen or pencil.

3. A pen or pencil holder comprising in 35 combination, a base, a clasp pivotedly secured to the back of said base, a pair of clamping members pivotedly disposed over said base, said clamping members being provided with jaws adapted to grip an article place thereinbetween, a spring adapted to 40 keep said clamping members in gripping position, and means for receiving the article and holding same against said base.

4. A pen or pencil holder comprising in 45 combination, a base, a clasp pivotedly secured to the back of said base, a pair of clamping members pivotedly disposed over the front of said base, said clamping members being provided at their upper ends with off-set extensions and at their lower ends with semi-cylindrical shaped jaws adapted to grip an article placed thereinbetween, a 50 spring adapted to keep said clamping members in engaged position, and means for receiving the article and holding same against said base.

5. As a new article of manufacture, a 55 pen or pencil holder comprising in combination, a base, a clasp pivotedly secured to the back of said base, an annular band

secured at right angles to said base, a pair of clamping members pivotedly secured to said band and parallel to said base, said 60 clamping members being provided at their upper ends with off-set extensions and at their lower ends with semi-cylindrical shaped jaws adapted to grip an article placed thereinbetween, a spring adapted to 65 keep said clamp-members in engaged position, a strap secured at right angle to said base, and another strap secured to said base intermediate said annular band and said former strap adapted to limit the outward 70 movements of said clamping members.

6. As a new article of manufacture, a pen or pencil holder comprising in combination a base, a clasp pivotedly secured to the back of said base, an annular band secured at 75 right angles to said base, a pair of clamping members pivotedly secured to said band and parallel to said base, said clamping members being provided at their upper ends with off-set extensions and at their lower ends 80 with gripping portions, said latter comprising a pair of toothed jaws, semi-cylindrical in shape, and frictional material attached to its inner surfaces, a spring adapted to keep said clamping members in gripping 85 position, a strap attached at right angle to said base, and another strap attached to said base intermediate said annular band and said former strap adapted to limit the outward 90 movements of said clamping members.

7. As a new article of manufacture, a pen or pencil holder comprising in combination, a base provided with pivot seats and a tongue intermediate said pivot seats, a clasp pivotedly secured in said pivot seats adapted 95 to engage said tongue, an annular band secured to said base, a pair of clamping members pivotedly secured to said band, said clamping members being provided at their lower ends with gripping portions, said 100 latter comprising a pair of toothed jaws, semi-cylindrical in shape, and frictional material attached to their inner surfaces, a spring adapted to keep said clamping members in gripping position, a strap attached 105 to said base, and another strap attached to said base intermediate said annular band and said former strap adapted to limit the outward movements of said clamping members.

Signed at Ossining in the county of West- 110 chester and State of New York this 11th day of March A. D. 1921.

JOSEPPE AMATO.
